[57] **CLAIM**

The ornamental design for a case for a removable disk drive cartridge, as shown and described.

DESCRIPTION

FIG. 1 is a perspective view of a case for a removable disk drive cartridge showing my new design;
 FIG. 2 is an inside perspective view thereof;
 FIG. 3 is a top plan view of FIG. 1;
 FIG. 4 is a bottom plan view of FIG. 1;
 FIG. 5 is a front elevational view of FIG. 1;
 FIG. 6 is a right side elevational view thereof;
 FIG. 7 is a left side elevational view thereof;
 FIG. 8 is a rear elevational view thereof;
 FIG. 9 is an inside elevational view of FIG. 2;
 FIG. 10 is a right side elevational view of FIG. 2;
 FIG. 11 is a left side elevational view of FIG. 9;
 FIG. 12 is a top plan view of FIG. 9;
 FIG. 13 is a bottom plan view of FIG. 9; and,
 FIG. 14 is an outside elevational view of FIG. 9.
